REINFORCED REEL FOR DYE KETTLES AND
THE LIKEWarren J. Simonds, Orange, Mass., assignor to
Rodney Hunt Machine Company, Orange,
Mass., a corporation of Massachusetts

Application March 30, 1936, Serial No. 71,627

3 Claims. (Cl. 242—118)

This invention relates to a reel for winding cloth or other material.

The principal objects of the invention are to provide a reel of strong and rigid construction which will use a smaller amount of lighter gauge metal than has been the case heretofore for the longitudinal strips which form the surface on which the cloth is wound; to provide means for reenforcing the entire reel; to provide a rigid construction of great strength but using only a small amount of material, and more specifically to provide one or more reenforced strips in a helical formation for strengthening the reel and enabling it to better resist the twisting action which occurs in this class of reels, thus improving the durability and strength of the reel.

Other objects and advantages of the invention will appear hereinafter.

Reference is to be had to the accompanying drawing, in which

Fig. 1 is a perspective view of a preferred embodiment of this invention;

Fig. 2 is a side view of a modification, and

Fig. 3 is a transverse sectional view on the line 3—3 of Fig. 2.

The conventional metal reel for use in winding cloth and the like has circular internal heads as 10 to support a series of longitudinal bars 11. This constitutes a simple device and, when they are built with the internal heads in addition to end discs 12, they have considerable strength but they fail on account of the continual bending of the bars 11 on account of the reel being stopped and started so many times in a dye kettle. In the old construction there is no reenforcement to prevent the twisting of the reel when it is stopped and started and the result is the breaking down of the metal itself by fatigue.

According to the present invention, the reel is reenforced by providing a helical rod 13 extending from the internal head 10 on one end to the corresponding internal head on the other

and preferably spot-welded at 16, or otherwise secured, to the flanges of the bars 11 which are shown in the form of angle irons. This constitutes a strong and rigid structure which, by its helical straps, resists twisting and therefore keeps the bars 11 in the same position and in the same condition for a long time. It is a permanent construction giving a long service. Furthermore, the helical reinforcement permits the use of lighter gauge metal for the bars 11, which metal is comparatively expensive. Thus, a most economical construction is provided. Of course, the longer the reel the greater the need of reenforcement against twisting and, if it is very long, a double helical reinforcement is employed as shown in Fig. 2, one of these rods, as 14, being left-hand and the other, as 15, being right-hand. This provides the desired strength and at a distinct saving.

Having thus described my invention and the advantages thereof I do not wish to be limited to the details herein disclosed, otherwise than as set forth in the claims, but what I claim is:

1. As an article of manufacture, a reel for dye kettles and the like comprising a head at each end, a series of longitudinal bars carried by said heads, and a reenforcing strip of metal having each end secured to one of said heads and passing around the reel bars and secured to said bars.

2. As an article of manufacture, a reel for textile goods comprising two end heads, a series of bars secured to said heads and extending from one to the other, and a helical reenforcing strip secured to the heads and to the bars from one end of the reel to the other.

3. As an article of manufacture, a cloth reel for a dye kettle comprising a series of longitudinal bars constituting the body of the reel and a pair of strengthening rods extending helically in opposite directions from one end to the other of the reel and secured to the said longitudinal bars.

WARREN J. SIMONDS.
